C-RING APPLYING AND REMOVING TOOL

Berneth M. Caldwell, Emo, Ontario, Canada

Application November 28, 1947, Serial No. 788,519

1 Claim. (Cl. 81—5.1)

1

This invention relates to improvements in plier-type tools and more particularly to an improved tool for applying and removing C-rings.

There is a general demand among technicians and mechanics for a single tool capable of spreading, holding and securing small objects in confined spaces. For example, there is no presently available tool which is suitable for both spreading, removing and replacing and clamping so-called C-rings, of sizes ranging from $\frac{1}{8}$ to $\frac{5}{8}$ inch as used in radios or the like, which is also useful for fine wire work such as that required on radio resistors and condensers.

It is therefore an object of this invention to provide an improved servicing tool, simple in design and adaptable to a plurality of dissimilar uses.

It is a further object of this invention to provide an improved spreading, holding and pincers tool of an elongated nature and extreme thinness which enables it to be used in radio work or the like where the component parts are closely spaced and usually of minimum size.

Another object of the invention is to provide an improved servicing tool of extreme thinness and a plier-like character which is capable of exerting relatively large spreading and clamping forces.

Other objects and advantages and adaptations will be recognized from the following description and the accompanying drawing, wherein:

Figure 1 is a side elevation of the combination tool holding a C-ring, a portion being broken away and shown in cross-section to better illustrate the construction thereof.

Figure 2 is an edgewise elevation of the tool.

Figure 3 is a side elevation of the tool in closed position.

Figure 4 is an illustration of the tool as it is adapted to be used for spreading a C-ring.

Figure 5 is a transverse cross-section on an enlarged scale taken substantially on line 2—2 of Figure 1.

Referring to the drawings, the improved tool, as shown in Figure 1, comprises a pair of pivotally connected levers generally indicated at 10, of generally rectangular cross-sectional shape and relatively thin in proportion to their width. These levers have mutually opposed straight edges 11 which extend from the inner ends of the jaws 12 to the inner ends of the curved handles 13 and are in contact when the tool is in its open or spread position, as illustrated in Figure 1. One of the levers is apertured near the inner end of its jaw portion and the other is provided with a pair of spaced apart, apertured lugs 14 to re-

2

ceive a pivot pin 15 which operatively connects the two levers together. The inner edge surfaces of the two jaws 12 are substantially straight and diverge outwardly at substantially equal angles from the pivotal connection between the jaws to provide a V-shaped recess between the jaws 12 when the levers are brought together with the edges 11 in contact, as shown in Figure 1. This aperture will receive various sizes of open C-rings, as indicated at 16, for compressing such rings into an annular groove in a rod. The outer edges of the levers are also substantially straight from the curved handles 13 to the outer ends of jaws 12 and are substantially parallel when the levers are in the closed position shown in Figure 1, but converge slightly from the handles to the outer ends of the jaws.

The jaws 12 are also convergently tapered on their opposite sides, as shown in Figure 2, so that their outer ends are sharply pointed. When the jaws are brought together by separating the handles 13, as shown in Figure 3, the jaw end of the tool provides a sharp point which may be forced between the ends of a compressed C-ring, as shown in Figure 4, after which the outer ends of the jaws are separated by compressing the handles 13 together so as to spread the jaws 12 to expand the C-ring so it may be removed from the groove in the rod 17.

The handles are exteriorly and interiorly curved to provide a comfortable hand grip for the tool and a finger space 18 between the handles so that they may be easily separated.

Each lever 10 is provided adjacent the pivot point between the two levers with an elongated recess 19 opening through the inner edge 11 thereof. A U-shaped spring 20 is mounted in the recesses 19 with its bight portion adjacent the pivot point and the ends of its legs directed outwardly away from each other and engaged in notches 21 provided in the bottoms of the recesses at the inner ends thereof. This spring is operative to resiliently urge the handle ends of the levers apart so that the tool is normally in the closed position illustrated in Figure 3 with the handles separated and the jaw 12 together, providing a sharp point at the jaw end of the tool.

To illustrate a specific operation of the tool as herein described, reference is made to Figure 50 4 wherein the pointed ends of the tool, being together in their normal state as shown in Figure 3, are inserted between the ends of C-ring 16 on shaft 17 preparatory to a spreading action by the exertion of a squeezing force on handles 55 13. For the replacement of a ring of this char-

acter on a shaft, the tool may be used to grasp the C-ring in the manner as shown in Figure 1, the jaw spreading force exerted by the spring 20 serving to hold the C-ring, and further spreading force being exerted manually on the handles 13 to squeeze the ends of the C-ring together to bind it on the shaft. In addition, if convenient or suitable, the inner edges 11 of handles 13 may be used to clamp a C-ring in place.

In utilizing this tool, for example, in wire work, as soldering, bending, etc., it will be readily recognized that the advantages of this straight, thin pointed tool is in its capability of manipulating, clamping, and retaining the work or piece to be worked in any desired position.

To facilitate the tool's use, it is further provided with a wire cutter formation 22 as more clearly shown in Figure 5. This formation is provided by cutting small semi-cylindrical recesses approximately half-way through one side of the levers 10 at the inner ends of the recesses 19 with the bottoms of the holes beveled to provide sharp wire-cutting edges, which lie in planes of the respective inner edges 11 and substantially meet when the levers are brought together to the position of Figure 1.

Having thus described my improved tool it will be obvious that the instrument is capable of a great many other plier-like uses, and that slight changes may be made therein without departing from the scope of the appended claim.

What is claimed is:

In a C-ring pliers, a pair of flat substantially straight levers positioned in side by side relation, pivot means pivoting said levers together at a point adjacent to but spaced inwardly from one end of said levers, said levers having confronting edges having first straight portions extending inwardly from said pivot means, said first straight edge portions being arranged to come into touching relation in the closed relation of the levers and to be in inwardly divergent relation in the spread position of said levers, the confronting edges of the levers having second straight por- 45

tions extending outwardly from said pivot means to the outer ends of the levers, said second straight portions diverging in an outward direction with respect to said first straight portions and constituting jaw faces, said jaw faces being arranged to be in touching relation in the spread position of the levers and to be separated in diverging relation in the closed position of the levers to receive a C-ring therebetween preliminary to closing the levers for compressing the C-ring, the outer edges of said levers extending outwardly from said pivot means being outwardly tapered to the outer ends of the levers to define sharp points at the outer ends of the levers, said sharp points being positioned together to form a single C-ring spreading point adapted to be positioned between the ends of a C-ring in the spread position of the levers preliminary to compressing the levers together for spreading the C-ring, and expanding spring means positioned between the levers at a point inwardly of said pivot means serving to normally position the levers in spread relation, said expanding spring means comprising longitudinal recesses formed in said first straight edge portion inwardly of said pivot means, and a U-shaped spring having a bight portion bearing against the outer ends of the recesses and divergent legs bearing against the bottoms of the recesses and the inner ends of the recesses.
